PORTABLE DISPLAY BOARD
CONSTRUCTION

Leon F. Urbain, Chicago, Ill.

Application April 6, 1950, Serial No. 154,264

5 Claims. (Cl. 35—65)

1

This invention is concerned generally with display boards such as chalk boards and tack boards and particularly with an ornamental and protective trim for portable chalk boards and tack boards.

Portable display boards such as chalk boards which can be marked on with chalk or crayon and portable tack boards on which papers and other items may be secured by thumb tacks are needed for educational purposes in rooms temporarily used as class rooms, on stages and in lecture halls and in other locations. Portable chalk boards and tack boards have great value as bulletin boards which can be positioned advantageously where they will attract the greatest possible attention. The materials from which modern chalk boards and tack boards are constructed are relatively light and hence easily carried about but are somewhat bendable and their edges are susceptible to wear and damage as by chipping and splintering.

The principal object of this invention is the provision of a portable display board having an edge trim to prevent wear and damage to the edges of said display board and to provide stiffening.

A more specific object of the present invention is the provision of a portable display board having an ornamental and protective edge trim readily attached thereto by conventional fastening means to prevent wear and damage to the edges of said display board.

A further object of this invention is the provision of a portable display board having an edge trim which includes integral structure adapted to receive article receiving means such as tack board strips and map holders.

Yet another object of this invention is the provision of a portable chalk board having an edge trim including an integral chalk and eraser supporting tray.

Yet another object of this invention is the provision of a portable display board construction having an edge trim constructed to secure two or more panels of such boards in juxtaposition.

Other and further objects and advantages of the present invention will be apparent from the following description when taken in connection with the accompanying drawings forming a part thereof.

In the drawings:

Fig. 1 is a perspective view of a portable chalk or tack board;

Fig. 2 is an enlarged sectional view in perspective taken along the line 2—2 of Fig. 1;

2

Fig. 3 is an enlarged sectional view in perspective taken along the line 3—3 of Fig. 1;

Fig. 4 is an enlarged sectional view taken along the line 4—4 of Fig. 1;

Fig. 5 is a view similar to Fig. 2 showing a modified form of the invention;

Fig. 6 is a similar view of a further modification;

Fig. 7 is a similar view of another modification;

Fig. 8 is a sectional perspective view similar to Fig. 2 showing an edge trim supporting two boards in back-to-back relation;

Fig. 9 is a view similar to Fig. 8 of a modified form of the invention;

Fig. 10 is a view similar to Fig. 3 and showing two boards in back-to-back relation;

Fig. 11 is a sectional perspective view of a center trim or divider securing two pairs of back-to-back boards in edgewise relation;

Fig. 12 is the form similar to Fig. 11 and showing a modified form of the invention.

In Fig. 1 there is shown a portable display board 14 comprising two chalk board panels 16 and 18 having a divider or center trim 20 placed between them. Head trim 22 extends over the upper edges of both panels while a chalk trough or bottom trim 24 is secured over the lower edges. The extreme outer edges are covered by side trim 26. Each of the trims provides stiffening for the boards.

The side trim 26 and head trim 22 are mitred at their joining corners to form an attractive and functional joint. Each of these three edge trims is similar and their construction will be understood readily with reference to Fig. 2 wherein the head trim 22 is shown in place on the chalk board panel 16. The head trim 22, Figure 2, comprises a channel member having a front wall 28 having a fluted front face for a pleasing appearance. A rear wall 30 which may be plain is spaced from the front wall 28 the thickness of the chalk board 16 and is maintained perpendicular to the front wall 28 by an interconnecting bight or edge wall 32. The rear wall 30 is shown as being bevelled at 32' along its lower edge to prevent its catching upon any article against which it may be leaned.

Modern chalk boards are generally made of fibrous material substantially similar in character to wood, and edge trim such as the head trim 22 may be secured thereto by wood screws 34 placed through spaced apertures in the rear wall 30 and screwed into the chalk board. The screws, being inserted from the rear, are invisible when the chalk board is in use.

The chalk trough 24 as may be seen in Fig. 3

is substantially similar to the head trim previously shown having a fluted front wall 36 and a rear wall 38 spaced therefrom by an edge wall 40. The rear wall 38 like the rear wall 30 is bevelled at its free edge 42. A chalk board 44 having an undulating surface extends outwardly from the top edge of the front wall 36 and is provided with a curled edge 46 to provide longitudinal stiffness and to place the edge where no injury can be sustained therefrom by a user. The upper surface of the inner edge of the chalk tray 44 is inclined upwardly as at 48 and terminated in a feather edge 50 in close contact with the chalk board 16 to insure that chalk dust sifting down the front surface of the board will be directed into the chalk trough 44 from whence it readily may be swept. The undulations of the chalk trough prevent erasers placed thereon from resting in such chalk dust and in chalk dust sifting from erasers on the trough. As some weight may be placed on the chalk tray 44 from time to time, means is provided for maintaining the front wall 36 against the front face of the chalk board panel 16. Opposed apertures are provided in the front and rear walls at spaced intervals and holes are drilled through the chalk board panel 16 in alignment therewith to receive split bolts each comprising a female member 52 and a male member 54 screwed thereinto. The apertures are provided relatively close to the chalk tray 44 so that the split bolts will provide the greatest possible support therefor and so the heads of these bolts will generally be hidden by the chalk tray 44.

The center trim or divider 20 as may be seen in Fig. 4 comprises a fluted front face or wall 56 having a rear wall 58 connected to and spaced therefrom by a transverse web 60. The walls and the web define a pair of channels receiving the chalk board panels 16 and 18 and the edges of the rear wall 58 are preferably bevelled as at 62. No screws or other fastening members are needed in the center trim 20 as the chalk board panels 16 and 18 are prevented from moving away from one another by fasteners in the head trim and chalk trough and are prevented from sliding relative to one another by the head trim and chalk trough. Although the two panels 16 and 18 have both been referred to as chalk boards it is to be understood that it is within the contemplation that either or both of these panels should be tack boards or display boards of any type.

In many instances it is desirable to provide a narrow tack board or slidable hangers at the top of a chalk board to secure papers, maps, and the like. The modification of the invention shown in Fig. 5 comprises a flute front face or wall 62 and a rear wall 64 spaced therefrom by an edge wall 66. The rear wall is preferably bevelled at its lower edge 68 and is apertured at intervals to receive wood screws for securing the trim to a chalk board 12 over which the trim is positioned. The upper and lower edges of the front wall 62 are provided with longitudinal outwardly extending and inturned confronting L-shaped flanges 74. The flanges 74 may secure a strip of cork or other tack board material or may slidably retain article supporting members.

A modified edge trim is shown in Fig. 6 which is mounted without depending in any way upon the screw retaining ability of the chalk board or tack board. Similarly to the structure shown in Fig. 2, the edge trim 76 comprises a fluted front wall 78 and a rear wall 80 having a bevelled lower edge 82. An edge wall 84 interconnects the front and rear walls 78 and 80. An intermediate longi-

tudinal wall or web 86 extends from the edge wall 84 parallel to the front and rear walls and spaced at a convenient distance from each. The upper edge of the chalk board or tack board panel 88 is provided with a longitudinal slot or kerf 90 providing adjacent panel sections between which the intermediate wall 86 is received. Spaced apertures are provided in the intermediate wall 86 in alignment with spaced apertures in the rear wall 80 to receive and retain sheet metal screws 92 threaded thereinto from the rear of the edge trim.

An edge trim for a portable chalk board is shown in Fig. 7 providing both a tack board and a map rail at the top of the chalk board. The edge trim 94 as shown in Fig. 7 comprises a substantially flat front wall 96 having a rear wall 98 spaced therefrom by an edge wall 100, the lower edge 101 of the rear wall again preferably being bevelled. The top and bottom edges of the front wall 96 are provided with outwardly extending and inturned confronting longitudinal L-shaped flanges 102 and with a substantially T-shaped flange 104 spaced therebetween. The lower flange 102 and T-shaped flange 104 secure a strip of cork 106 or other tack board material and a slidable map carrier 108 is secured by the upper flange 102 and T-shaped flange 104 interfitting with channels 110 therein. A hook 112 and spring clip 114 are carried by the carrier 108 so that when the trim 94 is slipped over the top edge of the chalk board 116 and secured thereto as by screws threaded into the rear thereof, maps and other permanent papers may be secured by hooks 112 and spring clips 114, and less permanent papers may be secured by thumb tacks extending through them into the tack board 106.

In Figs. 8-12 various edge and center trims are shown for mounting chalk boards and tack boards in back-to-back relation. By this means a single board construction may be used alternatively to be written upon by chalk or marking pencil or to have papers and the like affixed thereto by means such as thumb tacks. The backs of the chalk boards and tack boards are spaced slightly from one another so that the boards may expand and contract relative to one another with changes in temperature. The edge trim is somewhat resilient and the boards themselves possess some degree of resiliency so that the slight difference of the coefficients of thermal expansion of the two boards may be compensated for by slight deformation of the boards and of the edge trim.

As shown in Fig. 8 an edge trim 116 comprises two panel receiving channels 118 and 120 parallel to and spaced slightly from one another. The channels are defined by front and rear walls or faces 122 and 124 both of which are fluted longitudinally for attractive appearance, by an edge wall 126, and by a web 128 integral with the edge wall 126 and extending longitudinally intermediate the front and rear walls. A chalk board 130 fits between the front wall and the intermediate web while a tack board 132 comprising a panel 134 of cork or other tack receiving material and a panel 136 of stiffening material attached thereto is received in the channel 118. Spaced apertures are provided in the rear wall 124 in alignment with apertures in the web 128, and sheet metal screws 138 are screwed through these apertures. The screws 138 extend through the tack board 132 and into the chalk board 130 to secure both of these boards. The screws are held by the web 128 and hence need

not depend upon the screw retaining ability of either of the boards 130, 132. It is to be understood that although the walls 122 and 124 have been referred to as front and rear walls respectively, this is for purposes of identification only as which wall is the front wall and which wall is the rear wall depends upon which board is being used. It is within the contemplation of the invention that the board structure may be placed away from any wall so that both the chalk board and tack board may be used simultaneously.

Fig. 9 shows an edge trim which is particularly a head trim 140. The rear wall 142, edge wall 144 and longitudinal web 146 are similar to those shown in Fig. 8. The front wall 148 is fluted and is provided with longitudinal L-shaped flanges 150 and 152 extending toward one another on opposite edges of the wall and with an intermediate T-shaped longitudinal flange 154 placed between them. The three flanges define a pair of article receiving channels, 158 and 158. The upper channel 156 specifically comprises a map rail which may receive slideable members such as the member 102 shown in Fig. 7 while the channel 158 specifically secures a tack board strip 160 of cork or similar material. A chalk board 162 is received between the front wall and the web while a tack board 164 is received between the web and the rear wall. The head trim 140 is illustrated as secured by a split bolt comprising male and female members 166 and 168 placed through aligned apertures in the front and rear walls and the web, and threadedly engaging one another.

A chalk trough or bottom trim 170 is shown in use with a chalk board 172 and a tack board 174 in Fig. 10. The chalk trough comprises longitudinally fluted front and rear walls 176 and 178 respectively interconnected by a bottom or edge wall 180 bearing a longitudinal web 182. The front wall 176 has an upper feather edge 184 from which an inclined surface 186 extends outwardly to an undulating chalk and eraser receiving tray 188 having a curled under outer edge 190 for longitudinal stiffness. A split bolt comprising male and female members 192 and 194 threadedly engaging one another is placed through the front and rear walls and the web of the chalk trough as well as the chalk board and tack board to secure the boards and chalk trough to one another. The split bolt prevents the front wall 176 from being pulled away from the chalk board 172 when any force is applied to the top of the chalk and eraser tray 188.

It is contemplated that portable chalk and tack boards may be provided in back-to-back relation and divided either vertically or horizontally. Such division may be used when it is desired to provide additional stiffness to a large board structure or when it is desired to utilize both a chalk board and a tack board on the same side of the portable board structure. In Fig. 11 a horizontal separator or center trim 192 is shown joining two pairs of back-to-back members in edgewise relation. The divider 192 comprises longitudinally fluted front and rear walls 194 and 196 respectively joined by a horizontal transverse web 198. Upper and lower longitudinal webs 200 and 202 extend from the horizontal web 198 intermediate the front and rear walls and form with these walls and the horizontal web four channels receiving chalk boards 204 and 206 and reinforced or stiffened tack boards 208 and 210. The boards will be held from shifting in their respective planes

relative to one another by head, edge, and bottom trim such as that shown in Figs. 8 and 10 and it is not absolutely necessary that any means should be utilized for securing any of the boards to the divider 192. For purposes of added strength and security there is shown a fastener comprising a split bolt 212 extending through the front and rear walls and the upstanding web as well as through the chalk board 204 and tack board 208.

A modified form of the divider shown in Fig. 11 is shown in Fig. 12 and includes a map rail and a tack board on the chalk board face of the portable board structure. In Fig. 12 the divider 214 comprises a longitudinal fluted rear face or wall 216 interconnected with a fluted front wall 218 by a horizontal transverse web 220. The horizontal web is provided with upstanding and depending intermediate longitudinal vertically extending webs 222 and 224 respectively, spaced between the front and rear walls. The front wall 218 is provided at its upper and lower edges with longitudinally extending L-shaped flanges 226 and 228 inturned toward one another and is provided adjacent its midsection with a longitudinally extending T-shaped flange 230. The L-shaped and T-shaped flanges define upper and lower article receiving channels 232 and 234 respectively. The upper channel 232 specifically comprises a map rail while the lower channel specifically secures a tack board strip 236 of cork or other suitable material. Chalk boards 238 and 240 and reinforced tack boards 242 and 244 are received in the channels defined by the front and rear walls and the horizontal and upstanding and depending webs and are prevented from shifting by head, edge and bottom trim applied thereto. Additional strength and security are provided by a split bolt 246 extending through the rear wall 216, the front wall 218, the upstanding web 222 and through the chalk board 238 and tack board 242.

Portable display boards which are readily carried about and which will withstand rough handling have been disclosed herein. The display boards have great use wherever it is desired to illustrate a lecture, post notices, or otherwise visually impart information by marking with chalk or crayon or by temporarily supporting display material.

Although certain forms of trim have been disclosed herein it is to be understood that this is for illustrative purposes only and that my invention broadly includes all that which is set forth in the following claims.

I claim:

1. A portable display board construction comprising a pair of display panels having different coefficients of thermal expansion, a resilient extruded unitary protective trim mounted over corresponding edges of said panels and maintaining said panels in back-to-back relation, means for securing said protective trim over said edges, said trim comprising substantially parallel front and rear walls overlying outer surfaces of said panels adjacent said edges, an intermediate longitudinal web spaced between said front and rear walls and intermediate said panels to maintain them in spaced relation, and a wall integral with and maintaining said web and said front and rear walls in predetermined spaced relation.

2. A portable display board construction comprising a panel having front and rear faces and a lower edge, a chalk trough over said lower edge

comprising spaced front and rear walls overlying said front and rear faces adjacent said edge, said front wall having a surface engaging said front face, a bottom wall integral with and interconnecting said front and rear walls for maintaining said front and rear walls in predetermined spaced relation, an eraser and chalk supporting tray extending outwardly from said front wall and having a supporting surface, said supporting surface and said front wall surface meeting at an acute angle, and securing means extending between said front and rear walls and through said display panel to maintain both of said walls in close contact with the front and rear faces of said panel.

3. A portable display board construction comprising a panel having front and rear faces and an edge, a unitary extruded trim over said edge and means for securing said trim over said edge, said trim comprising a rear wall along said rear face, a front wall along said front face and having means defining at least one article supporting channel extending forwardly from said front wall, and an edge wall maintaining said front and rear walls in predetermined spaced relation.

4. A portable display board construction comprising a unitary extruded divider including front and rear walls, a transverse web maintaining said front and rear walls in predetermined spaced relation, a pair of intermediate longitudinal webs extending from said transverse web and substantially parallel to said front and rear walls defining therewith four display panel receiving channels, and four display boards received in said channels in back-to-back pairs edgewise of one another.

5. A portable display board construction for display boards, panels and blackboards comprising a relatively flexible display panel having a substantially uniform relatively narrow cross sectional thickness, said panel having front and rear parallel faces of substantially large area as compared to such cross sectional thickness and said panel having wear susceptible edges, a substantially elongated, rigid, extruded metal trim protectively enclosing at least one of the peripheral edges of such panel, fastening means securing said protective trim over said edge, said trim comprising substantially rigid, substantially parallel, and substantially long spaced apart front and rear walls, said front and rear walls each in cross sectional thickness being of the order of substantially less than one third of the cross sectional thickness of said panel, the inner

5
